UNITED STATES PATENT OFFICE.

MICHEL R. CASTILLE, OF OPELOUSAS, LOUISIANA.

DISPLAY APPARATUS.

Application filed August 22, 1925. Serial No. 51,847.

This invention relates to display apparatus and has for its object the provision of means whereby a lecturer or public speaker may have at hand means for refreshing his memory so that he may speak uninterruptedly without fear of being embarrassed by a loss of memory as to the text of his address. The invention seeks to provide a reminder mechanism which will be under control of the speaker at all times and which will be so disposed as not to be visible to the audience. The invention also has for its object the provision of means whereby the device will be operated efficiently at all times and will not be apt to get out of order. The invention resides in certain novel features which will be hereinafter first fully described and then more particularly pointed out in the appended claim.

20 In the drawings, which illustrate one embodiment of the invention,

Figure 1 is a vertical sectional elevation of a portion of an assembly hall having my invention included therein;

25 Fig. 2 is an enlarged detail perspective view showing the arrangement of the operating parts of the invention;

Fig. 3 is an enlarged sectional elevation of the display cabinet with the door thereof 30 in open position;

Fig. 4 is a central longitudinal section through the cabinet with the door in closed position;

Fig. 5 is an enlarged detail section of part 35 of the means for supporting the display strip or web, and

Fig. 6 is an enlarged detail view of a supporting bracket and portion of the gears carried thereby.

40 In the drawings, the reference numeral 1 indicates a platform or stage upon which a speaker will stand when delivering an address or lecture, a desk 2 being erected at the front of the platform and being equipped

45 with a vertical rail 3 at its front side which projects above the top 4 thereof. Above the platform 1 is a roof 5 which may be a part of the roof of the building in which the platform is located, or may be the entire

50 roof when the platform is located for open air speaking. The roof projects beyond the front of the platform, as shown at 6, whereby to overhang the desk 2, and at the front of the roof is a rail or other support 7 which is preferably at such height that it may be easily observed by the speaker upon the

platform 1 but will not attract the attention of the audience seated or standing in front of the platform. Secured to the rail 7 which may, furthermore, constitute a part of the eaves of the roof 5, is a cabinet 8 having a swinging door 9 provided with a sight opening 10, the door being normally closed so that matter within the cabinet may be easily seen through the opening 10 by the speaker. The platform and the desk may be illuminated in any desired manner and the greatest efficiency will be attained by providing lamps 11 upon the under side of the roof 5 immediately over the cabinet 8 so that the sight opening 10 thereof will be directly lighted and matter appearing back of the sight opening, therefore, easily read. Within the cabinet are supported rollers 12 and 13 and carried by these rollers is a web 14 upon which has been previously printed notes of the lecture or address to be delivered, or, if desired, the entire text of the address. These rollers are provided with longitudinal slits 15 in which the ends of the web 14 are engaged so that, if the rollers be rotated, the length of the web will be wound thereon and, consequently, the ends will be held in the respective slits, it being understood, of course, that the web in practice is wound upon one roller and then transferred from the same to the other roller as the delivery proceeds. The lower roller 13 initially carries the entire length of the web 14, except so much thereof as is needed to securely engage it with the upper roller 12, the intermediate portion of the web passing over a supporting plate 16 which is disposed immediately adjacent the sight opening 10 and has its upper and lower edges made 90 convex so that the web may pass smoothly and easily over the backing plate without liability of tearing. The rollers 12 and 13 are, of course, assembled so as to facilitate the placing of a web thereon or the removal 100 of a web therefrom and to support the lower roller in its proper position a stud 17 is secured upon one side of the cabinet to engage a socket in the adjacent end of the roller, as will be understood upon reference to Fig. 3. 105 At the opposite end of the roller, a resilient bracket 18 is secured in the cabinet to bear against the end of the roller and hold it in engagement with the stud 17 while a pin or stud 19 is engaged in the bore or socket 110 in the roller and passes through the free end portion of the said bracket 18, as shown

clearly in Fig. 5. This pin or stud 19 has an enlarged socketed outer end 20 which is engaged by the inner end of a stem 21 passing through the wall of the cabinet and equipped at its outer end with a head 22. A spring 23 is coiled around the stem 21 between the side of the cabinet and the socket 20 so as to hold the socket toward the bracket 18 and thereby yieldably maintain the pin or stud 19 in engagement with the roller. When it is desired to release the roller, an outward pull upon the head 22 will obviously withdraw the pin 19 and permit the roller to be disengaged from the stud 17 and withdrawn from the cabinet. The upper roller 12 is supported at one end by a second stem 21 and stud 19 but the opposite end thereof is formed with spaced sockets 24 to be engaged by spaced studs upon a head or disk 25 which is disposed at the inner end of a hub 26 which passes through and is rotatably engaged in the side wall of the cabinet. The outer end of the hub 26 is provided with a socket 27 having flat walls to be engaged by the flat-sided end 28 of an operating shaft 29.

The shaft 29 is supported in suitable bearing brackets upon the rail or beam 7 and extends to the side of the arch or proscenium opening in front of the platform, a beveled pinion 30 being secured upon the outer end of the said shaft to mesh with a similar beveled pinion 31 upon the front end of a shaft 32 which extends along the side of the arch to a point in the vertical plane of the desk 2, being equipped at its rear end with a beveled pinion 33 corresponding to the pinions 30 and 31 and meshing with a beveled pinion 34 upon the upper end of a shaft 35 which is disposed vertically at the side of the proscenium opening and extends downwardly to a point just above the desk, as shown. The lower end of the shaft 35 carries a beveled pinion 36 meshing with a beveled pinion 37 secured upon the end by a roller or hand-controlled shaft 38 which extends across the top of the desk 2 behind the rail 3 thereof so that it will be hidden from the audience by the said rail. Bearing brackets, such as 39, are secured upon the side of the arch immediately adjacent the roof so as to support the adjacent ends of the shafts 29, 32 and 35, and these brackets also provide the bearings in which the ends of said shafts will revolve. At the lower end of the shaft 35 and the adjacent end of the controlling roller 38, a bracket 40 is secured upon the desk and this bracket has an upstanding resilient end member 41 which supports the end of the roller 38, and an outwardly turned overhanging lip 42 at the upper end of the upstanding member, the said lip furnishing a bearing and support for the lower end of the shaft 35. The form of brackets employed serve to maintain the meshing pinions in their operative relation while at the

same time they are very simple and inexpensive and may be very easily secured in place.

To maintain the web taut between the rollers 12 and 13 and prevent excessive movement thereof, a leaf spring 43 is secured in the bottom of the cabinet and bears upon that portion of the web which is wound upon the lower roller 13, as clearly shown in Fig. 4. The spring constitutes a brake frictionally engaging the wound portion of the web so that, while the web may be unwound from said roller as the controlling roller or shaft 38 is rotated, this movement will be arrested and it will be held taut and smooth upon the supporting plate 16 instantly when the action of the controlling roller stops.

From the foregoing description, taken in connection with the accompanying drawings, it is thought the manner of using my apparatus and the advantages of the same will be readily understood and appreciated. Public speakers are frequently embarrassed because, in the course of their remarks, they depart more or less from the pre-arranged text and upon returning to the original theme find that they have forgotten the prepared text immediately following that which preceded the digression. Many lecturers or public speakers are enabled to follow the pre-arranged argument by reference to short memoranda or notes, but other speakers are obliged to closely follow the original text in order to maintain the sequence of their discourse. My invention provides means whereby a speaker may have at hand means entirely under his control whereby proper reminders of the text will be constantly before him and embarrassing interruptions in delivery will be avoided. Prior to the opening of the lecture hall the web, having the address printed or written thereon, is placed in the cabinet and mounted upon the rollers 12 and 13 in such position that the text may be easily read by the speaker through the sight opening 10 while, of course, the audience will not be able to see the cabinet nor any of the motion transmitting shafts, inasmuch as the decorations of the platform and the opening through which the audience views the platform and the speakers thereon may be so arranged as to completely hide all of the working parts. The speaker will, of course, be delivering the greater portion of his address immediately behind the desk and may rotate the shaft or roller 38 by one hand as he needs to consult the prepared text. Should he digress from the pre-arranged matter, the controlling roller 38 will be permitted to remain stationary during the impromptu remarks, and when it is desired to resume the original discourse, a glance at the cabinet will show the speaker how and where to proceed.

My apparatus is exceedingly simple and compact and may be easily installed in any place intended for public assemblies. It will be understood that the sight opening in the cabinet will be glazed in order to protect the text carrying web, and, preferably, a magnifying glass will be employed for this purpose in order that distance between the speaker and the cabinet will not prevent 10 the ready reading of the matter appearing upon the web.

Having thus described the invention, I claim:

Means for prompting a speaker comprising in combination with a desk, and a roof

overhanging the desk and having a depending portion forwardly of the desk, of a cabinet mounted upon the depending portion of the roof and having a sight opening in its rear side, a prompting web, rollers within the cabinet above and below the sight opening thereof, one of the rollers having the said web wound thereon, a shafting connected with the other roller and having a portion extending along the said desk for rotation by the speaker to unwind the web from one roller and wind it upon the other roller.

In testimony whereof I affix my signature.

MICHEL R. CASTILLE. [L. s.]
